INVENTOR.

UNITED STATES PATENT OFFICE.

RAPHAEL MERTIN MERTZ, OF TOLEDO, OHIO.

DESIGN FOR A LENS-MOUNTING FOR EYEGLASSES.

SPECIFICATION forming part of Design No. 31,131, dated July 4, 1899.

Application filed April 17, 1899. Serial No. 713,413. Term of patent 3½ years.

To all whom it may concern:

Be it known that I, RAPHAEL MERTIN MERTZ, of Toledo, county of Lucas, and State of Ohio, have invented a certain new and original Design for a Lens-Mounting for Eye-glasses; and I do hereby declare that the following is a full, clear, and exact description thereof, which will enable others skilled in the art to which it appertains to make and use the same, reference being had to the accompanying drawings, and to the figures of reference marked thereon, which form part of this specification.

My design has reference to a lens-mounting for eyeglasses.

In the drawings, Figure 1 is an enlarged front elevation of my invention embodying my design. Fig. 2 is a rear elevation thereof. Fig. 3 is a side elevation.

As shown in the drawings, the leading or material features of my design are as follows: the ears 2, in parallel relation and having the

adjacent faces flat and the outer faces slightly rounded; the straps 3, extending in approximately opposite directions; the neck 1, cylindrical in form, extending from straps 3, and the tubular portion 4, disposed at right angles to the cylindrical neck 1 and having on one end thereof the claws 5. Tubular portion 4 is also formed with a cut-out portion 6 in alinement with the longitudinal axis of neck 1.

Having described my design, what I claim, and desire to secure by Letters Patent, is—

The design for a lens-mounting for eye-glasses, substantially as shown and described.

In testimony that I claim the foregoing as my own I affix my signature in presence of two witnesses.

RAPHAEL MERTIN MERTZ.
